(57) **CLAIM**

The ornamental design for a base for an inverted bottle holder, as shown and described.

DESCRIPTION

FIG. 1 is a top perspective view of a base for an inverted bottle holder, showing my new design;

FIG. 2 is a front elevation view thereof, the rear, the right-side, and the left-side elevation views being mirror images thereof;

FIG. 3 is a top plan view thereof;

FIG. 4 is a bottom plan view thereof; and,

FIG. 5 is a top perspective view of the base for an inverted bottle holder shown in a used condition.

The broken lines showing an inverted bottle holder in FIG. 5 depict environmental subject matter that forms no part of the claimed design.
